UNITED STATES PATENT OFFICE.

JAY G. HOYT, OF GENEVA, AND WILLIAM MAIR, OF BATAVIA, ILLINOIS,
ASSIGNORS TO THE W. H. HOWELL COMPANY, OF GENEVA, ILLINOIS.

DESIGN FOR A FLUTING-IRON.

SPECIFICATION forming part of Design No. 27,207, dated June 15, 1897.

Application filed March 20, 1897. Serial No. 628,540. Term of patent 14 years.

To all whom it may concern:

Be it known that we, JAY G. HOYT, residing at Geneva, and WILLIAM MAIR, residing in Batavia, in the county of Kane and State 5 of Illinois, citizens of the United States, have invented and produced a new and original Design for Fluting-Irons, of which the following is a specification.

In the drawings, Figure 1 is a side elevation of a rocking fluting-iron. Fig. 2 is a plan of the same, and Fig. 3 is a section on the line 3 3 of Fig. 2.

The main feature of our design consists in a rocking fluting-iron curved from end to end, 5 and having a raised cross-bar located centrally upon its upper or back surface.

In the drawings, A represents the iron, which, as seen, is curved from end to end. At the center of its back or top surface is a raised bar C, arranged transversely of the 20 iron and resting upon two posts D D. At each end are raised projections E E.

We claim—

The design for a rocking fluting-iron, substantially as shown.

JAY G. HOYT.
WILLIAM MAIR.
